[57] CLAIM

The ornamental design for a dialing pad, as shown and described.

DESCRIPTION

FIG. 1 is a front view illustrating a dialing pad according to our new design;

FIG. 2 is a back view thereof;

FIG. 3 is a side elevational view from the left thereof;

FIG. 4 is a side elevational view from the right thereof;

FIG. 5 is a top plan view thereof;

FIG. 6 is a bottom view thereof;

FIG. 7 is a perspective view thereof;

FIG. 8 is a reduced top perspective view of a dialing pad mounted on an automobile dashboard, and in this position the plug attached to the cable is hidden from view. The broken lines are shown for illustrative purposes only.

FIG. 1

FIG. 2

FIG. 3
